CIRCUMCISER

Frank A. La Breck, Eau Claire, Wis.

Application April 24, 1936, Serial No. 76,240

8 Claims. (Cl. 128—305)

The instrument forming the subject matter of this application is adapted to carry out the operation of circumcision expeditiously, novel means being provided for positioning the glans penis and the prepuce properly to facilitate the amputation of the prepuce, and novel means being supplied for amputating the prepuce without disagreeably sanguine results, either operative or post-operative.

0 It is within the province of the disclosure to improve generally and to enhance the utility of devices of that type to which the invention appertains.

With the above and other objects in view, which 5 will appear as the description proceeds, the invention resides in the combination and arrangement of parts and in the details of construction hereinafter described and claimed, it being understood that changes in the precise embodiment of the invention herein disclosed, may be made 10 within the scope of what is claimed, without departing from the spirit of the invention.

In the accompanying drawing:

Fig. 1 shows in longitudinal section, an instrument constructed in accordance with the invention, parts being in elevation;

Fig. 2 is a top plan;

Fig. 3 is a longitudinal section of the combined penis rest and prepuce insert, parts being broken away.

30 In the following description, it will be assumed that the instrument is in the position of Fig. 1, rather than in one of the many other positions it may assume in use, such terms as "upper" and "lower" being selected accordingly, to define the 35 relative positions of parts.

The numeral 1 marks a tubular handle, including a disk like head 2 having a neck 42 secured to the upper end of the handle by threading, and by a screw 15 hereinafter described. Traction 40 members 3 for the prepuce 50, in the form of outwardly bowed resilient fingers, are provided, the lower ends of the traction members being securely mounted in the edge of the head 2. The traction members 3 terminate at their upper ends 45 in outwardly extended, pointed hooks 4, adapted to be inserted into the prepuce, as shown in Fig. 3, although the degree that the hooks extend into the prepuce is a matter of operative surgery, the drawing being part of the description of the 50 mechanical construction of the instrument, rather than plates for the guidance of a surgeon.

The device comprises a group of parts that may be called an actuator, the function of which is to cause the traction members 3 to draw down

the prepuce about the penis rest 30 (hereinafter described) to the place where the amputation of the prepuce is to occur. The actuator includes a tube 5, journaled in the handle 1, but held against longitudinal movement therein, the tube 5 having a solid upper end 6 provided with an external circumferential groove 7 receiving the inner end of a screw 8 or other projection, mounted in the handle 1 and holding the tube 5 therein for rotation but against longitudinal movement. 10 An operating wheel 9 is located at the lower end of the handle 1, and has a neck 19 secured to the tube 5 by a screw or other attaching element 10.

A plunger 11 has longitudinal reciprocation in the head 2 of the handle 1, but cannot rotate therein, because a key screw 15 is engaged at its inner end with a longitudinal key way 14 in the plunger 11. The key screw 15 is mounted in the neck 42 of the head 2 and in the handle 1, and aids in securing the head 2 to the handle 1, as aforesaid. The plunger 11 is provided with a stem 12, threaded into the end 6 of the tube 5 and extended downwardly within the handle 1, into the tube 5. The plunger 11 has a reduced, 25 threaded upper end 16, forming a transverse shoulder 17 in the plunger.

The numeral 18 marks a U-shaped frame including a disk-like foot 20, threaded on the upper end 16 of the plunger 11, into abutment with the shoulder 17, and therefore fixed to the plunger. The foot 20 carries outwardly-extended, upwardly-curved arms 21. The foot 20 of the frame 18 has notches or seats 22 in its edge, the notches or seats receiving the traction members 3 closely but slidably. The arms 21 of the frame 18 terminate in transverse bearings 23. The bearings 23 and the adjacent portions of the arms 21 are provided with small openings 24. Anchor pins 25 are mounted on the arms 21, close to, and 30 below the openings 24.

Tubular tensioners 26 have longitudinal movement in the bearings 23, in a direction at right angles to the plunger 11. The tensioners 26 are supplied with external longitudinal grooves 27 receiving the inner ends of key screws 28 mounted in the bearings 23, the construction being such that although the tensioners 26 can move endwise, they cannot rotate. The tensioners 26 are provided near their outer ends with small transverse 45 holes 29. The tensioners 26 are threaded at 44 into operating members 43, in the form of wheels or disks, the hubs of which abut against the outer ends of the bearings 23.

The numeral 30 marks a penis rest and prepuce 55

insert, comprising a body 31 mounted on the end 16 of the plunger 11. The body 31 preferably is threaded on the end 16 of the plunger 11, but this is not insisted upon. The body 31 has a recess 32 in its outer end and is provided with a reduced portion 33 forming a transverse circumscribing shoulder 34. A strong but thin and light ring 35 surrounds the part 33 of the body 1 and abuts against the shoulder 34. The ring 35 has an external circumferential seat 36. The ring 35 is provided with a notch 37 in its lower edge, the notch receiving a lug 38 on the body 31, the construction being such that when the body 31 is rotated, the ring 35 will participate in the rotation.

In order to secure a rotation of the entire penis rest and prepuce insert 30, the body 31 thereof is supplied with a hole 45 (Fig. 1), adapted to receive a detachable outstanding handle 46 (Fig. 2). The ring 35 and the recess 32 in the body 31 are shaped to receive the end of the glans penis, and it is on this account that the member 30 is called a penis rest.

The operation of the device will be described simply, and in the language of mechanics rather than in the nomenclature of surgery, latitude being allowed for the technique preferred by the individual operator, and it being assumed that local anaesthesia and proper sterilization will not be overlooked.

By means of the wheel 9, the tube 5 is rotated, and the plunger 11, the frame 18 and the penis rest 30 are carried down from the solid line position of Fig. 1, with respect to the traction members 3, until the traction members converge above the rest 30. The prepuce 50 is retracted with respect to the glans penis, and then is advanced over the hooks 4 on the traction members 3, the prepuce being impaled on the hooks. Reverse rotation is imparted to the wheel 9, and the plunger 11, the frame 18 and the member 30 are carried upwardly, the end of the penis being seated in the ring 35 and in the recess 32 of the body 31, and the prepuce being pulled down over the ring 35, by the hooks 4, the bends of the hooks riding down over the outside of the ring 35 and over the outside of the body 31, and the member 30 then becoming a prepuce insert, as shown in Fig. 3. In this way, the place of amputation in the prepuce 50 is disposed opposite the seat 36 of the ring 35. The prepuce may be secured to the ring 35 by a ligature 51.

The outer ends of severing members, such as thin, flexible wires 52, are extended through the openings 24 in the bearings 23 and are engaged with the anchor pins 25 on the arms 21. The wires 52 are wrapped in one or more convolutions about the prepuce 50. The outer ends of the wires 52 are extended through the bores of the tensioners 26 and are secured in the transverse holes 29 of the tensioners. The wheels 43 are rotated, and move the tensioners 26 outwardly in opposite directions, the convolutions of the wires 52 being tightened, and the prepuce 50 being bound tightly in the circumferential seat 36 of the ring 35, against the ring.

The operator now inserts the handle 46 (Fig. 2) in the hole 45 (Fig. 1) of the body 31 of the member 30 and oscillates the member 30, including the ring 35, about an axis, the convolutions of the wires 52 severing the prepuce 50.

After the operation has been concluded, the ring 35 is left engaged with the prepuce 50, for such a period as the operator may determine, the prepuce

being held on the ring 35 by the ligature shown at 51. Because the ring 35 is left secured to the prepuce for a time, and owing to the crushing effect of the convolutions of the wires 52, as distinguished from a knife-like incision, there will be a minimum amount of bleeding, and practically no bleeding. After a period determined by the judgment of the operator, the ligature 51 is detached, and the ring 35 is removed from the prepuce 50, there being then no danger of annoying 10 hemorrhage.

The instrument is simple in construction and in operation, and affords a means whereby a practically bloodless circumcision operation may be consummated.

The rest 30 may be made in different diameters, the rests being interchangeable to meet conditions attendant upon the operation.

What is claimed is:

1. A circumcision instrument comprising a penis rest, a tractor movable longitudinally of the rest, to draw the prepuce over the rest, a severing member, means for holding the severing member in operative relation to the rest, and means for rotating the rest with respect to the severing member, to effect a severing of the prepuce.

2. A circumcision instrument comprising a penis rest, a tractor movable longitudinally of the rest, to draw the prepuce over the rest, a flexible severing member, means for drawing the severing member taut against the rest, and means for rotating the rest with respect to the severing member, to effect a severing of the prepuce.

3. A circumcision instrument comprising a penis rest including a body and a ring carried by the body, a tractor movable longitudinally of the rest, to draw the prepuce over the rest, a severing member, means for holding the severing member in operative relation to the rest, means for rotating the rest to effect a severing of the prepuce, the ring being removably mounted on the body and means for securing the ring to the unsevered portion of the prepuce, whereby the ring will remain on unsevered portion of the prepuce after circumcision has been accomplished.

4. A circumcision instrument comprising a handle, a frame, a prepuce tractor carried by the handle, a penis rest carried by the frame, a flexible severing member mounted on the frame, means for producing relative movement between the frame and the handle, to cause the tractor to draw the prepuce over the rest and to bring the rest into the field of operation of the severing member, and means for rotating the rest with respect to the severing member.

5. A circumcision instrument comprising a frame having arms, a penis rest mounted between the arms, a flexible severing member disposed in a convolution about the rest, means for securing one end of the severing member to one arm, means carried by the other arm for tightening the severing member, and means for rotating the rest with respect to the severing member.

6. A circumcision instrument comprising a handle, a prepuce tractor mounted on the handle, a plunger having longitudinal movement in the handle, a frame carried by the plunger, a penis rest on the intermediate portion of the frame, in operative relation to the tractor, a flexible severing member extended across the frame and secured thereto in operative relation to the rest, and means for rotating the rest with respect to the severing member.

7. A circumcision instrument comprising a

frame, having arms, a penis rest on the frame and located between the arms, a flexible severing member extended across the rest, and means on the arms for holding the severing member and 5 tightening it with respect to the rest.

8. A circumcision instrument comprising a frame having arms, a penis rest on the frame and located between the arms, tensioners movable on the arms, flexible severing members disposed in

convolutions about the rest, means for securing one end of each severing member to one arm, means for securing the opposite end of each severing member to the tensioner of the other arm, and means for imparting movement to the tensioners, 5 to tighten the convolutions with respect to the rest.
